UNITED STATES PATENT OFFICE

2,441,329

INSULATED RAIL JOINT

Ralph W. Payne, Washington, D. C.

Application March 26, 1946, Serial No. 657,097

3 Claims. (Cl. 238--159)

1

This invention relates to insulated rail joints, and has particular reference to improvements in insulated rail joints of the type in which head and base pieces of insulation are interposed between end splice bars and the end portions of the rails and in which the head pieces of insulation are covered by protective metal shield pieces, all as generally disposed in my prior patent, No. 2,016,214 of October 1, 1935.

Insulated rail joints of the type referred to are in extensive use, and in such joints the head pieces of insulation and their covering, protective, metal shield pieces extend to the extreme ends of the splice bars to afford desirable loading cooperation between the splice bars and the rails as far out as the extreme ends of the joints. This, however, exposes the outer portions of the ends of the metal shield pieces to damaging blows by dragging brake rigging and other equipment, with the result that the ends of the shield pieces may sometimes be bent downwardly and forced through the insulating head pieces into contact with the splice bars, thereby producing short circuits causing serious signal troubles.

Accordingly, one special and important object of the present invention is to provide an insulated rail joint of the type referred to in which at least the outer portions of the metal shield pieces terminate at their ends short of the ends of the splice bars, whereby they are protected by the ends of the splice bars against receiving damaging blows and being bent or deflected into contact with the splice bars by dragging brake rigging or other equipment.

It is desirable that the splice bars have loading cooperation as far out as their extreme ends with the rails. Consequently, it is desirable that the portions of the head pieces of insulation and the metal shield pieces through which the splice bars take loading engagement with the rails, extend to the extreme ends of the splice bars to afford such loading cooperation. Accordingly, another special and important object of the present invention is to provide an insulated rail joint of the type referred to in which the outer portions of the metal shield pieces terminate short of the ends of the splice bars, and in which the portions of said pieces through which the splice bars have loading cooperation with the rails, extend to the ends of the splice bars to afford desirable loading cooperation between the rails and the splice bars as far outwardly as the ends of the latter.

Another special and important object of the 55 outer portions of said shield pieces. Conse-

2

invention is to provide an insulated rail joint of the type referred to in which the head pieces of insulation and their covering metal shield pieces are interchangeable to enable the life of the joint to be considerably prolonged.

With the foregoing and other objects in view, which will become more fully apparent as the nature of the invention is better understood, the same consists in an insulated rail joint of the type referred to embodying the novel features of construction, combination and arrangement of parts as will be hereinafter more fully described, illustrated in the accompanying drawings and defined in the appended claims.

In the accompanying drawings, wherein like characters of reference denote corresponding parts in the different views:

Figure 1 is a side elevation of an insulated rail joint embodying the features of the invention.

Figure 2 is a transverse half-section, showing the joint in end elevation; and

Figure 3 is a top plan view of one end portion of the joint.

Referring to the drawings in detail, R, R, designate the meeting end portions of a pair of railway rails, and B designates a splice bar connecting said rail end portions together.

Interposed between the bases of the rail end portions R, R, and the base of the splice bar B are base pieces of insulation 10, while engaged over the top of the splice bar B are head pieces of insulation 11 of inverted U-shape in cross section which are covered and protected by metal shield pieces 12, likewise of inverted U-shape in cross section, all in accordance with known practice as disclosed, for example, in my aforesaid prior patent.

In accordance with the present invention, at 40 least the portions of the metal shield pieces 12 which are disposed outwardly of the portions thereof through which the splice bar takes loading cooperation with the rail end portions R, R, do not extend to the ends of the splice bar B, but

45 terminate suitable distances short of the ends thereof, as indicated at 13. Therefore, the outer, exposed portions of said shield pieces are pro-

tected at their ends by the ends of the splice bar against receiving damaging blows by dragging

50 brake rigging or other equipment, since such dragging equipment will strike one end or the other of the splice bar, depending upon the direction of train movement, and thereby will be de-

flected over or from the ends of the exposed

55 outer portions of said shield pieces. Conse-

quently, damage to the ends of the shield pieces by dragging brake rigging or other equipment is, by the present invention, practically eliminated, with the result that any possibility of said shield pieces being forced through the insulation into contact with the splice bar and causing a short circuit is practically eliminated.

The portions of the insulating head pieces 11 which are disposed outwardly of the portions thereof through which the splice bar takes loading cooperation with the rails may extend to the ends of the splice bar or, like the corresponding portions of the metal shield pieces 12, may terminate short of the ends of the splice bar, as desired.

The portions of the insulating head pieces 11 and of their covering shield pieces 12 through which the splice bar takes loading cooperation with the rails may also terminate short of the ends of the splice bar B. Preferably, however, these portions extend to the extreme ends of the splice bar to afford desirable loading cooperation between the rails and the splice bar as far outward as the extreme ends of the latter.

The drawings illustrate the invention as being embodied in a rail joint of the standard type in which the splice B has head loading cooperation with the under sides of the heads of the rails. It is to be understood, however, that this merely is by way of example and that the joint may be of the headfree or any other type. Likewise, it is to be understood that the rails as well as the splice bars may be of any types other than the particular types shown.

A feature of the invention is that the head pieces of insulation 11 and their covering shield pieces 12 are of duplicate construction at their ends whereby they are interchangeable to compensate for wear as well as for repair purposes, thus materially to increase the life of the joint.

From the foregoing description considered in connection with the accompanying drawings it is believed that the construction and operation of the present protector will be clearly understood and its advantages appreciated. It is desired to point out however, that while only a single specific embodiment of the invention has been illustrated and described, the same is readily susceptible to various modifications within the scope of the appended claims.

I claim:

1. An insulated rail joint comprising the rails, the splice bar, and head pieces of insulation and covering metal shield pieces of inverted U-shape in cross section engaged over the top of the splice bar and including inner portions interposed between the head of the splice bar and the rails through which the splice bar has head loading cooperation with the rails, said inner portions of said insulating and said shield pieces extending as far outwardly as the ends of the splice bar, the portions of said shield pieces which are disposed outwardly of said inner loading portions thereof terminating at their outer ends short of the ends of the splice bar.
2. An insulated rail joint as set forth in claim 1 in which the insulating head pieces and their covering shield pieces are of duplicate construction at their ends whereby they are interchangeable.
3. An insulated rail joint, comprising the rails, the splice bar, and head pieces of insulation and covering metal shield pieces of inverted U-shape in cross section engaged over the top of the splice bar and including inner portions interposed between the head of the splice bar and the rails and through which the rails have loading cooperation with the splice bar, the outer ends of the said inner portions of said insulating and said shield pieces being disposed as far outwardly as the ends of the splice bar, the outer portions of said metal shield pieces having their outer ends terminating short of the outer ends of the splice bar, and the outer portions of said insulating pieces having their outer ends extending beyond the outer ends of the outer portions of said metal shield pieces.
